FOREIGN PATENT DOCUMENTS

CN 302061303 S 9/2012

Primary Examiner — Ian Simmons*Assistant Examiner* — Janice Lim(74) *Attorney, Agent, or Firm* — Charles S. Sara; DeWitt Ross & Stevens S.C.(57) **CLAIM**

The ornamental design of a dispensing container, as shown and described.

DESCRIPTION

FIG. 1 is a front perspective view of a dispensing container, showing my new design;

FIG. 2 is a front cross-sectional view thereof, taken in the direction of line 2-2 of FIG. 6;

FIG. 3 is a side cross-sectional view thereof, taken in the direction of line 3-3 of FIG. 4;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines shown in the drawings are included for purpose of illustrating environmental structure and form no part of the claimed design.

1 Claim, 5 Drawing Sheets(56)
